to Memory Vase Company, Cleveland, Ohio, a corporation of Ohio

Application June 4, 1952, Serial No. 20,038

Term of patent 3½ years

(Cl. D35—3)

To all whom it may concern:

Be it known that I, Lawrence E. Blazey, a citizen of the United States, residing at Bay Village, in the county of Cuyahoga and State of Ohio, have invented a new, original, and ornamental Design for a Combined Cemetery Grave Flower Holder and Base Therefor, of which the following is a specification, reference being had to the accompanying drawing, forming a part thereof, in which:

Fig. 1 is a side elevational view of a combined cemetery grave flower holder and base therefor in a closed position, showing my new design;

Fig. 2 is a top plan view of the combined cemetery grave flower holder and base therefor as shown in Fig. 1;

Fig. 3 is a bottom plan view of the combined cemetery grave flower holder and base therefor as shown in Fig. 1;

Fig. 4 is a side elevational view showing the combined cemetery grave flower holder and base therefor in an upright service position;

Fig. 5 is a top plan view of the combined cemetery grave flower holder and base therefor as shown in Fig. 4; and

Fig. 6 is an enlarged view thereof.

I claim:

The ornamental design for a combined cemetery grave flower holder and base therefor, substantially as shown.

LAWRENCE E. BLAZEY.
